UNITED STATES PATENT OFFICE.

ARTHUR WEIGELT AND WILLIAM HERMS, OF ST. LOUIS, MISSOURI.

DESIGN FOR A MECHANICAL JUMPING FROG.

SPECIFICATION forming part of Design No. 30,032, dated January 17, 1899.

Application filed December 19, 1898. Serial No. 699,778. Term of patent 3½ years.

To all whom it may concern:

Be it known that we, ARTHUR WEIGELT and WILLIAM HERMS, citizens of the United States, residing in the city of St. Louis, State of Missouri, have invented and produced a new and original Design for a Mechanical Jumping Frog, of which the following is a specification.

Figure 1 is a top plan view of a mechanical jumping frog embodying our design, and Fig. 2 is a side elevation.

As shown in the drawings, the leading or essential feature of our new design for a mechanical jumping frog consists of the plate 3,

the front legs 4 extending downwardly from the sides of the forward end of the plate and the hind legs 5 extending upwardly, forwardly, then downwardly and backwardly from the sides of the rear end of the plate 3.

We claim—

The design for a mechanical jumping frog substantially as herein shown and described.

ARTHUR WEIGELT.
WILLIAM HERMS.
